FRAME CONSTRUCTION

Filed Feb. 3, 1931

UNITED STATES PATENT OFFICE

1,965,580

FRAME CONSTRUCTION

Charles M. Dill, Manoa, Pa.

Application February 3, 1931, Serial No. 513,191

6 Claims. (Cl. 35—15)

My invention relates to building construction, and the object of my invention is to provide a neat, substantial and ornamental frame for enclosing card panels, bulletin boards, blackboards, and the like, more particularly designed for use in class rooms of school buildings; such frame forming the final finish between the black-board or panel structure and the wall receiving the same, and closing the gap between the wall and such board or boards.

A further object of my invention is to place the black-board, panels, etc., and/or the supports therefor, in a recess in the wall, and to carry edge portions of such frame into the recess past the edge of the plaster or other wall finish at the margin of such recess. Since the black-boards, panels, etc., are placed entirely within the recess left in the plaster in the use of my invention, it is not necessary to wait until the plaster dries out before erecting the black-boards, panels, etc., thus saving material time in the construction of the building.

These and other features of my invention are more fully described hereinafter; reference being had to the accompanying drawing, in which:

Figure 1 is a front elevation, partly broken away, of my improved construction illustrating a card panel, bulletin board, and black-board combination enclosed by the frame structure forming the subject of my invention.

Fig. 2 is an enlarged sectional view taken on the line II—II, Fig. 1; illustrating the chalk tray portion of the black-board and showing also a sectional view of the frame disposed adjacent thereto.

Fig. 3 is a fragmentary plan view of an end portion of the chalk tray showing also a sectional view of the frame at the side of the black-board.

Fig. 4 is a cross-sectional view of a portion of the frame taken on the line IV—IV, Fig. 1, and

Fig. 5 is a sectional view illustrating a modified form of chalk tray construction.

The usual practice in placing black-boards, bulletin boards, card panels and/or the like upon the walls of class rooms, is to mount them upon such wall and to enclose them in a heavy wooden frame, which frame is of a size that materially reduces the area of the black-board, panel and/or the like.

In carrying out my invention, the wall 1 is recessed at 2 for the reception of supports 3 for the black-board, panel boards, bulletin boards, etc., indicated at 4, 5 and 6 respectively. The recess receiving the combined board structure is slightly oversize in order that the board and panel struc-

ture may be readily set in place, even before the plaster or other wall finish is dry; the gap at the bottom being indicated at a, in Fig. 2; the gap at the side being indicated at b, Fig. 3, and a gap that may exist between separate sections 60 of the boards or panels, is indicated at c in Fig. 4.

The frame, preferably of metal, designed to enclose the several slabs or surfaces making up the combined structure, is indicated generally at 10. This frame comprises a continuous outer or marginal portion 10^a, and division sections 10^b disposed between and/or covering the joints between the several panels and/or board sections, and connected to said portion 10^a.

The outer or marginal portion 10^a of the frame 70 comprises a flange portion A engaging the surface of the several boards or panels, with a box-like portion B in the form of a raised rim constituting the actual margin of the frame, and a flange C, continuous with the box-like portion B, 75 and extending into the gap which lies between the board or panel structure and the edges of the wall recess receiving the same. The frame sections are adjusted to the boards or panels when being mounted so that this flange C may be placed 80 in such position as to closely engage the plaster or other wall finish at the edge of the opening or wall recess and thereby provide a definite closure for the gap that would otherwise exist between the board or panel structure and wall. The portions A and B of the frame section are of ample extent to cover the edge of the board or panel and permit positioning so that the flange portion C may be spaced away from the board to the desired extent and engage the plaster or other 90 wall edge. The frame may be secured in place by screws 11 which may pass through the flange portion A of the same and through the black-board or panel and enter one of the supporting members 3.

The secondary or inner frame members 10^b cover the joints between the respective board and panel sections and are preferably of the cross-sectional contour indicated in Fig. 4; comprising a box-like portion B' and side flange portions 100 A' integral therewith and in parallel relation. The several sections making up the frame are neatly fitted together with miter joints at the several meeting points, as clearly indicated in Fig. 1, and these joints may be made permanent 105 by welding, brazing, or the like.

A chalk tray 12, preferably of metal, is associated with the frame enclosing the board and panel structure, and this may be of the cross-sectional contour illustrated in Fig. 2. Such tray 110

underlies the board and panel structure, and the lower portion of the marginal frame 10^a is so arranged that the flanged portion A of the same overlies the top of the rear portion of such tray; which rear portion may overlie and be secured to a support 3^a carried by the wall 1 below the board and panel structure. The chalk tray may have end walls 12^a designed to prevent the chalk and erasers usually carried thereby dropping off. In Fig. 5 I have illustrated a modified form of chalk tray, in which the tray portion is entirely below the board and panel structure and extends rearwardly beneath the same; such arrangement cutting down the amount of projection into the room. In this form of arrangement, the rear portion of the tray includes a flange 12^b which may be secured to the wall 1 by screws. In each instance, the apron of the chalk tray may be secured to backing members 3^a by suitable screws.

While in most instances the plaster or other material which may be used as a wall finish at the edges of the recess receiving the board and panel structure will present sharp corners against which the flange C of the frame sections may abut, substantially at right angles to the surface of such plaster, I may employ a plaster terminal of the type illustrated in the patent of Baum, No. 1,727,953, at the several edges of such recess.

While I have shown a combination black-board and panel structure, it will be understood that my improved frame construction may be employed with one or more black-boards alone, or one or more panels alone, disposed in a recess of the wall upon which it is mounted, without departing from my invention.

My improved frame construction provides, in the raised rim B at the marginal edges thereof, a barrier that will prevent dirty water resulting from washing of the black-boards and/or panels, or the chalk or other dust wiped from the black-boards and/or panels, staining the adjacent plaster or other wall finish. At the same time such frame may be readily wiped or polished without marring or smudging the adjacent wall surface.

While I have referred to the use of a metal frame, it will be understood that I may employ forms of molded material, bakelite, or various forms of synthetic plastic bodies, without departing from my invention.

50. I claim:

1. The combination, with a black-board adapted to be mounted in a recess larger than the blackboard, in a wall, of a frame enclosing said black-board having a flange overlying the edges of the latter for supporting the same, and a flange closing the gap between the edges of the recess and board; said latter flange being spaced from the edge of the board to engage the wall of the recess.

60. 2. The combination, with a black-board adapt-

ed to be mounted in a recess, larger than said blackboard, in a wall, of a frame enclosing said black-board; said frame having a flange overlying the edge of the board for supporting the same, a flange closing the gap between the edges of the recess and said board, and a raised rim portion between said flanges, said last-named flange being continuous with one wall of said raised portion and spaced from the edge of the board and engaging the wall of the recess whereby an unbroken frame is provided extending from the edge of the recess to the edge of the blackboard.

3. The combination, with a black-board adapted to be mounted in a recess, larger than said blackboard, in a wall, of a frame enclosing said black-board; said frame comprising a flange overlying the edges of the black-board for supporting the same, and a flange closing the gap between the edges of the recess and the board; said latter flange being of length sufficient to extend rearwardly of the face of the board and spaced from the edge of the latter to engage the wall of the recess.

4. The combination, with a black-board, and supports for the same adapted to be mounted in a recess, larger than the blackboard, in a wall, of a frame of metal enclosing the edges of said black-board; said frame having a flange overlying the edge of the black-board and an extended flange at right angles to the first-named flange and adapted to enter the gap between the board, its supports and the edge walls of said recess and abut said latter walls and thereby close the gap between the blackboard and the edge of the recess.

5. The combination, with a black-board adapted to be mounted in a recess, larger than said blackboard, in a wall, of a frame of metal enclosing the edge of said black-board; said frame having a flange overlying the edge of the black-board for supporting the same and a flange at right angles to the first-named flange and extending rearwardly into the gap between the board and the edges of said recess and abut the latter edges to close the gap between the board and the edges of the recess, and a chalk tray partially disposed under the black-board and under the rearwardly extending flange of the frame, whereby said flange assists in supporting said chalk tray.

6. The combination with a member adapted to be mounted in a recess, larger than said member, formed in a wall, of a frame enclosing said member and having a flange overlying the edges of the latter for supporting the same and a flange closing the gap between the edges of the recess and the member; said latter flange being spaced from the edge of the member to engage the wall of the recess.
